UNITED STATES PATENT OFFICE

JAMES F. HAYNES, OF MURFREESBORO, TENNESSEE

MENU HOLDER

Application filed May 3, 1930. Serial No. 449,539.

This invention relates to menu holders, an object being to provide means for holding a menu card or sheet in such manner that it may be easily read, and in addition will be protected against soiling and other damage.

Another object of the invention is the provision of a menu holder having means for illuminating the menu so that the latter may be clearly read in the dark, the invention being especially adapted for use at curb or roadside refreshment stations.

Another object of the invention is the provision of a menu holder having a combined handle and menu illuminating means, whereby the illuminating means may be controlled by the same hand used for holding the menu.

With the above and other objects in view, the invention further includes the following novel features and details of construction, to be hereinafter more fully described, illustrated in the accompanying drawings and pointed out in the appended claim.

In the drawings:

Figure 1 is an elevation of a menu holder constructed in accordance with the invention.

Figure 2 is an edge view of the same.

Figures 3 and 4 are enlarged sectional views taken respectively on the lines 3-3 and 4-4 of Figure 1.

Figure 5 is an enlarged fragmentary sectional view taken on the line 5-5 of Figure 1.

Figure 6 is a perspective view showing a slightly different form of the invention, the latter being open and a portion of the handle broken away.

Figure 7 is an enlarged sectional view taken substantially on the line 7-7 of Figure 6.

Figures 8, 9 and 10 are sectional views showing modified forms of the holder.

Referring to the drawings in detail wherein like characters of reference denote corresponding parts, the improved holder comprises a casing 10 having means for removably receiving a menu card or sheet 11, the latter being positioned within an envelope or pocket 12, made of transparent material. This envelope or pocket permits of the use of a relatively thin menu sheet, the envelope or

pocket both stiffening or reinforcing the sheet and protecting the same against damage.

The casing includes a back 13, and side walls 14, the front wall being formed by the pocket and menu. The casing along opposite side edges of the front wall is provided with opposed grooves 15 to receive the pocket, while the top of the casing has hingedly secured thereto as shown at 16, a cover plate 17. Hinged to the cover plate as shown at 18 is an apron 19 which extends transversely across the upper edge of the front of the holder and is yieldingly held in position by means of a spring latch 20.

The holder is provided with a handle 21 which is preferably in the form of an ordinary flashlight. The casing of the flashlight has one end secured within an opening provided in the casing 10 and within a collar 22 which surrounds this opening. The bulb 23 of the flashlight extends into the lower part of the casing 10, and the switch 24 is positioned upon the outside of the casing. The battery for supplying current to the bulb 23 is of course positioned within the flashlight 75 casing.

The flashlight provides a combined handle and illuminating means for the menu and the said illuminating means may be operated by the same hand which holds the menu. 80 When the switch 24 is closed, the bulb 23 will be lit to illuminate the interior of the casing, and as the pocket 12 is transparent, and the menu sheet 11 of thin material, the menu will be properly illuminated so as to be conveniently read. While the light will be sufficient to permit the menu to be easily read, the eyes of the reader will be protected from the glare of the light.

The collar 22 is threaded as shown in Figure 4 of the drawings so that the flashlight may be removably secured in position.

In Figures 6 and 7, the casing 25 is provided with inwardly extending flanges 26 around its front edge, and the menu sheet 27 is covered by a suitable transparent panel 28, while a frame 29 is hingedly secured to the casing as shown at 30. This frame carries pins 31 which pass through openings 32 provided in the transparent panel 28 and 300

through openings in the menu sheet, so that when the frame 29 is closed the menu sheet will be securely held in position. The frame 29 is provided with a resilient latch 33 which engages a keeper 34 extending from the casing 25.

In Figure 8, the casing is provided with a reflector 35 which is inclined with respect to the front wall of the casing, the said front wall being formed by a transparent envelope 11', similar to the envelope described in connection with Figures 1 to 5 of the drawings. In this form of casing the front wall is parallel with the rear wall 36, while the top of the casing is closed by a hinged cover 37 having a flange 38 at its forward edge. The flashlight and handle 21' is secured within the casing as shown.

In Figure 9, the front wall 39 of the casing is inclined and this wall is provided with spaced openings 40 from the upper edges of which extend downwardly inclined flanges 41. The menu sheet 42 is positioned against this front wall 39 and is covered by a transparent panel 42. Light from the flashlight 21' will strike the lower faces of the flanges 41 and be reflected through the menu sheet and transparent panel, the menu sheet being so positioned that the articles indicated thereon will be over the openings 40. The top of the casing is closed by means of a cover 17' similar to the cover used in connection with the first described form of the invention.

In Figure 10 the casing is provided with an electric bulb 43 which receives current through conductors 44 from a battery 45. Current to the lamp is controlled by a switch 46 which is mounted upon the handle 47 of the holder. The menu sheet 48 may be removably arranged within a transparent envelope or pocket 49, and the latter removably secured within the holder. A hinged cover 50 closes the upper end of the holder while a reflector 51 is arranged within the holder around the bulb 43 so as to reflect the light through the menu sheet.

The invention is susceptible of various changes in its form, proportions and minor details of construction and the right is herein reserved to make such changes as properly fall within the scope of the appended claim.

Having described the invention what is claimed is:

A menu holder comprising a handle, a manually controlled light located at the end thereof, a casing mounted upon the handle above the light and having a groove disposed in a plane lying at an acute angle to the axis of the handle, a translucent sheet removably located in the groove of the casing and a cover hinged to the casing and adapted to close the said groove.

In testimony whereof I affix my signature.
JAMES F. HAYNES.
